UNITED STATES PATENT OFFICE.

LOUIS A. MINEA AND ALBERT J. ZSCHOCKE, OF ST. PAUL, AND STEPHEN J. RAUCHWARTER, OF BELLEPLAINE, MINNESOTA; SAID RAUCHWARTER ASSIGNOR TO SAID MINEA AND ZSCHOCKE.

STATION-INDICATOR.

1,056,756.

Specification of Letters Patent.

Patented Mar. 18, 1913.

Continuation of application Serial No. 621,372, filed April 15, 1911. This application filed March 8, 1912. Serial No. 682,383.

To all whom it may concern:

Be it known that we, LOUIS A. MINEA, ALBERT J. ZSCHOCKE, and STEPHEN J. RAUCHWARTER, citizens of the United States, 5 whose residences are, respectively, as follows, 395 Bellows avenue, St. Paul, 572 Hall avenue, St. Paul, and Belleplaine, all in the State of Minnesota, have invented new and useful Improvements in Station-Indicators, 10 of which the following is a specification.

Our invention relates to improvements in station indicators. Its object is to provide a device for cars adapted to automatically indicate each succeeding station *en route*.

15 A further object of our invention is to provide a station indicator having its indicating mechanism removably attached to the car and designed to be detachably connected with the stationary mechanism of any desired car, to obviate the changing of the indicating aprons from one mechanism to the other.

20 A further object is to provide a station indicator for cars adapted to automatically indicate the stations as the car advances and to reverse as the car backs or turns at the end of the line.

25 A further object is to provide a station indicator, simple and durable in construction, having an electrically operated indicating apron capable of being reversed and moved at equal distances during each operation irrespective of the varying diameter of the spools on which the same is wound.

30 In the drawings Figure 1 is a side elevation of the indicating mechanism; Fig. 2 is a plan view of the same with the indicating apron removed; Fig. 3 is a side elevation showing in section the operating switch for 35 controlling the driving mechanism; Fig. 4 is a plan view of the operating switch; Fig. 5 is an end elevation of the same; Fig. 6 is a front elevation of the reversing switch showing its driving mechanism; Fig. 7 is a 40 plan view of the same; Fig. 8 is a side view of the drop adapted to operate the controlling switch; Fig. 9 is an end elevation of the same; Fig. 10 is a view showing the indicating apron as seen from the interior of 45 the car in which it is mounted; Figs. 11 and 12 are detail views of the ratchet driving disk; and Fig. 13 is a diagrammatical view of the wiring in our improved station indicator.

Referring to the accompanying drawings, 55 the indicating mechanism designated by the letter A is designed to be detachably mounted in a car and is electrically connected with the operating switch B and the reverse switch C.

60 The indicating mechanism A is constructed as follows: The drive shaft 10 is rotatably mounted in the casing 11 and supports the ratchet wheel 12, the gear wheel 13 and the sprocket wheel 14. The lever 15 is pivotally mounted on the shaft 10 and supports at one end the dog magnets 16 and 17 and the dog 18. The dog 18 is pivotally mounted on the lever 15 and is designed to engage the ratchet wheel 12. The dog magnet 16 65 operates the dog 18 to engage the ratchet wheel 12 and rotate it in one direction, and the magnet 17 operates said dog to engage said ratchet wheel and operate it in the other direction. The spring stop 19 70 engages the dog and yieldingly holds it in one of its positions in engagement with the ratchet wheel 12. The link 20 is pivotally connected to the casing 11 at one end and to the lever 15 at the other. The arm 21 is pivotally mounted on the casing 11 and is connected by the spring 22 with said link 20. The electromagnet 23 is arranged below the arm 21 and is adapted to draw its free end down. The spring catch 24 on the casing 11 is adapted 75 to engage and hold said arm in its lowest position. The lug 25 on the lever 15 is arranged to strike and release this catch to free the arm 21. The spring 26 is connected at one end to the casing 11, and at the other, 80 to the link 20, the end of said link connected to the lever 15 being drawn upward and normally held in engagement with the stop 27 by said spring. The shaft 28 is rotatably mounted in the casing 11 and supports the 85 drive roller 29, the gear wheel 30, and the sprocket wheel 31. The shaft 32 is rotatably mounted in the casing 11 and supports at one end the beveled friction wheel 33 and at the other the fixed ratchet disk 34 and the 90 idler sprockets 35 and 36. The spools 37 and 38 are rotatably mounted in the casing 11 and on one end of the spool 37 is feathered a beveled friction wheel 39, and on one end of the spool 38 a beveled wheel 40 is similarly mounted. The wheels 39 and 40 are 95 yieldingly held against the face of the wheel 33 by the springs 41 and 42 respectively, as

60

65

70

75

80

85

90

95

100

105

shown in Fig. 2 of the drawings. The apron 43 is attached at one end to the spool 37 and extends from the bottom thereof around the guide rollers 44 and 45, the drive roller 29 and the anti-slipping roller 46 to the bottom of the spool 38 as shown in Fig. 1. Said rollers 44, 45 and 46 are idlers freely rotatable in the casing 11. The last mentioned roller holds the apron 43 in frictional engagement with the drive roller 29. The names of the stations are placed upon the apron 43 and are so spaced that one name at a time will appear in a position between the guide rollers 44 and 45, so that the name 15 may be seen through the glass 47 in the casing 11. The hooks 48 on the casing 11 are designed to engage the hooks 49 in a car to form a detachable connection between said casing and car.

20 In operation and assuming the arm 21 to be in its normal position, and the dog magnet 17 to have operated and moved the dog 18 to a position engaging the ratchet 12 to operate the same in a counter clockwise direction as seen in Fig. 1, the electro-magnet 23 is charged as hereinafter described and instantly draws the free end of the arm 21 downward into position in engagement with the catch 24. The movement of this arm is 25 then yieldingly transmitted to the link 20 through the spring 22, against the action of the spring 26, thus raising the dog 18 which engages the ratchet wheel 12 and rotates the shaft 10. The arm 21 is held by the catch 24 after the magnet 23 is demagnetized and until the spring 22 pulls the lever 15 to position, releasing said catch by the engagement of the lug 25 therewith. Upon the releasing of this lever the link 20 is raised by the action 30 of the spring 26. The rising of the link 20 causes the downward movement of the dog 18 which, then passes over the ratchet 12. The rotation of the shaft 10 drives the roller 29 by means of the gears 13 and 30. The disk 34 is provided with ratchets on each face. The idler sprockets 35 and 36 are arranged on opposite sides of this disk and are provided with spring arms 51 adapted to yieldingly bear against said ratchets. The 35 sprocket 36 is connected by the chain 52 to the sprocket 31 on the shaft 28 and the sprocket 35 is connected by the chain 53 to the sprocket 14 on the shaft 10. The sprockets 35 and 36 are driven in opposite directions upon the rotation of the shaft 10 in either direction. The spring arms 51 engage the disk 34 to rotate the same and its shaft 32 only when their respective sprockets are rotated in a clock-wise direction, as seen 40 in Fig. 1. The apron 43 is moved by the roller 29, a predetermined distance, to move the name of the station first seen through the glass 47, and present in its place a new name. The friction wheel 33 as shown in 45 Fig. 1 moves in a clock-wise direction and

tends to drive the spool 37, by means of the friction wheel 39, in the opposite direction. If it were not for the positive action of the drive roller 29, the apron would be wound on the spool 37 by the friction between the 70 wheels 33 and 39, but this positive action unwinds it against the retarding effect of said friction wheels. The spool 38 is rotated in a counter clock-wise direction by the wheel 40, and winds the apron thereon as it passes from the drive roller 29. Assuming the dog magnet 16 to have operated and moved the dog 18 to a position engaging the ratchet wheel 12, as shown in dotted lines in Fig. 1, said dog passes over the ratchet 12 on the downward movement of the link 20 and arm 21, but engages said ratchet on the upward movement of the same and operates the shaft 10 in a clock-wise direction. The rotation of the drive wheel 29 is reversed, the apron 43 being then unwound from the spool 38 against the friction of the wheels 33 and 40, and wound on the spool 37 as it passes from the guide rollers 45 and 44. The unwinding of the apron 43 from the spools 37 and 38 90 against the action of the friction wheels 33, 39 and 40 prevents slack in the apron between said spools and insures an accurate movement and spacing of the same.

The operating switch B is adapted to 95 form an electrical connection between the electro-magnet 23 and a source of electric current, and is shown in use with a trolley commonly used in electric street railways. We do not limit ourselves to any particular 100 source of electrical energy or class of vehicle, as it is evident that our indicating mechanism A may be operated through the operating switch B in connection with the third rail type of cars, or on ordinary steam cars 105 supplied with a portable source of electric current, as well as other forms of conveyance.

The operating switch B and its associated mechanism is constructed as follows: The 110 drop 54 is attached to and offset from the trolley wire 55. The plate 56 is attached to the wire 55, and one of its guy wires to form a support from which the drop 54 is braced. The grooved pulley 57 is rotatably mounted at the upper end of the bell crank 58 to engage the drop 54 as the trolley pole 59 passes said drop. The bell crank 58 is pivotally connected to the pole 59 at 60, and also at its lower end to the plunger 61. The cylindrical body portion 62 of the switch B is pivotally connected at one end to the pole 59, and is provided with insulated contact barrels 63 and 64 and the terminal plates 65. The plunger 61 is slidably mounted within the casing and is provided with the spring 66 within said casing and with the spring 67 without said casing. The springs 66 and 67 are designed to normally hold the plunger 61 in a position free from engage- 120

130

ment with the barrels 63 and 64, and the terminal plates 65, and also to hold the wheel 57 in position to engage the drop 54. The guard 68 is mounted on the pole 59 and protects the wheel 57 and the bell crank 58 from the trolley guy wires, in case the trolley pole 59 becomes disengaged from the trolley wire 55. One of the drops 54 is located on the trolley wire between successive stations and 5 engaging the wheel 57 as the car advances, causes the plunger 61 to move to a position in contact with the barrel 64. At the end of the line is placed a drop 54 of greater width than the drops used between the stations, as 10 shown in dotted lines in Fig. 8. This drop engages the wheel 57 and moves the plunger 61 to a position in electrical contact with the terminal plates 65.

The reverse switch C is provided for operating the dog magnets 16 and 17 to reverse the movement of the apron 43, and is electrically controlled through the operating switch B and the motorman's reverse lever 69, as will be more fully hereinafter described. The ratchet switch wheel 70 is mounted on the plate 71 and is engaged and rotated in a clock-wise direction, as seen in Fig. 6 by the pawl 72; said pawl being pivotally connected to the arm 73. 25 The spring 74 is arranged to yieldingly retain the bar 73 in an elevated position against the stop 75, and the spring 76 is arranged to yieldingly engage the pawl 72 with the ratchets of the wheel 70. The magnet 77 is positioned below the arm 73 and draws said arm downward to rotate the wheel 70, step by step, when an electrical connection is made between said magnet and circuit, either by the switch B or the 30 motorman's reverse lever 69. The insulated contact plates 78 and 79 are mounted in diametrically opposed positions, the opposite plates constituting pairs, said pairs being alternately in electrical connection with the 35 dog magnets 16 and 17. The spring arm 80 is fixed to the wheel 70 and at each partial revolution of said wheel a contact is made by said arm between one of the pairs of plates 78 or 79 to operate one of the dog magnets 40 16 and 17.

Referring particularly to the diagrammatical representation of the wiring in Fig. 13, and assuming the wheel 57 to be in contact with the drop 54, the electric current 45 passes from the generator 81 through said drop to the wheel 57; then through the bell crank 58 and the plunger 61 to the contact barrel 64, which at this time is in engagement with said plunger. The barrels 63 and 50 64 are connected through the wire 82 to the operating electro-magnet 23 and through it to the ground by the wire 83. When the above described connection is made the magnet 23 is charged and draws the arm 21 and 55 connected link 20 in a downward direction.

After said connection is broken as the wheel 57 passes from engagement with the drop 54, the arm 21 and link 20 are drawn upward by the spring 26. This movement operates the lever 15 and causes the apron 43 to move in a direction fixed by the position of the dog 18 as above described. The contact plates 78 are connected by the wires 84 to the magnet 16, and the plates 79 are connected by the wires 85 to the magnet 17, 70 said magnets 16 and 17 being connected through the wire 86, the trolley pole 59 and trolley 55 with the generator 81. The arm 80 is grounded through the wire 83 and in engaging the plates 78 completes the 75 circuit through the magnet 16, and in engaging the plates 79 completes the circuit through the magnet 17. The reverse switch magnet 77 is connected with the terminal plates 65 by the wire 87, and with the brush 80 plate 88 by the wire 89, and is also grounded through the wire 83. The motorman's reverse lever 69 is connected by the wire 90 with the trolley 55, and is provided with a brush 91 adapted to engage the plate 88, 90 when said lever is moved into position to propel the car in either direction. The engagement of the plunger 61 with the plates 65 and the engagement of the brush 91 with the plate 88 completes the circuit through 95 the magnet 77 and in either case causes the arm 80 to move and engage the next succeeding pair of contact plates to operate one of the magnets 16 and 17 and reverse the position of the dog 18. The plug 92 is arranged 100 in the circuit to facilitate the removal of the indicating mechanism A from one car and to permit an easy connection with another. This arrangement is desirable to obviate the changing of the aprons 43 from one of the 105 casings 11 to another.

In operation, the wheel 57 engages the drops 54 as the car passes between stations and causes the electro-magnet 23 to be energized and move the indicating mechanism A 110 to advance the apron 43. At the end of the line or loop, the wheel 57 engages one of the wider drops 54 as shown in dotted lines in Fig. 8 and causes the plunger 61 to engage the plates 65 of the switch B to operate the magnet 77. The action of this magnet operates the reverse switch C and thus changes the position of the dog 18 to reverse the movement of the apron. The wheel 57 is engaged by the drops 54 and a contact is made between the plunger 61 and the 115 barrel 63. The drive magnet 23 is energized through this connection and causes the apron to move, thus indicating each succeeding station as the car backs. In turning the reverse lever 69 to advance the car, the 120 magnet 77 is energized through the connection at the lever 69, and operates the switch C to reverse the movement of the apron. The wheel 57 is engaged by the drops 54 and a contact is made between the plunger 61 and the 125 barrel 63. The drive magnet 23 is energized through this connection and causes the apron to move, thus indicating each succeeding station as the car backs. In turning the reverse lever 69 to advance the car, the 130

reverse switch C is again operated to advance the apron 43. In case of an interruption in the usual route, the apron 43 may be moved by hand to indicate the proper station on the changed route by oscillating the hand operating rod 93. The reverse switch C being adapted to govern the direction in which said apron travels, is first set in its proper position by the rod 94 which is connected thereto as shown in Fig. 6 of the drawings.

Having described our invention, what we claim as new and desire to protect by Letters Patent, is:

15. 1. In a station indicator for cars, an apron containing the names of stations, spools for receiving said apron, a drive roller, electrically actuated means in operative yielding connection with said roller for driving the same to advance the apron and a catch adapted to hold said electrically actuated means at one limit of its stroke and to insure complete movement of the drive roller and apron.
20. 2. In an indicator, spools, a drive roller, an apron on said roller and spools, electrically actuated driving means in operative yielding connection with said roller for rotating the same, electrically actuated means for reversing the action of said driving means and a catch adapted to hold said electrically actuated driving means at one limit of its stroke and to insure complete movement of the drive roller and apron.
25. 3. In an indicator, an apron provided with spools for receiving the same, a drive roller for said apron, an arm in operative, yielding connection with said roller and spools for rotating the same, electrically actuated means for moving said arm, means adapted to engage and secure the arm at one limit of its movement and means for releasing said arm.
30. 4. In an indicator, a frame, a pair of spools revoluble in said frame, an apron attached at one end to one spool and at its other end to the second spool, the ends of said apron being wound on said spools in the same direction, a drive roller for moving the apron, driving means for rotating said roller, and a friction wheel in operative connection with said driving means and spools tending to rotate the latter identically as to time, direction and speed.
35. 5. In an indicator, for electric cars, the combination with the lever for reversing the car of an apron having spools for receiving the same, a drive roller for moving said apron, electrically actuated driving means for rotating said roller, electrically actuated reversing means in operative connection with said lever for reversing the car for changing the rotation of said roller, a source of electric current, a switch and drops for operating said switch to complete the circuit between said driving and reversing means and the source of current.
40. 6. In an indicator, an apron, spools for receiving the apron, a drive roller for moving said apron, driving means for rotating said roller in both directions, a friction wheel in operative connection with said driving means and friction wheels on said spools in yielding engagement with said first mentioned wheel, said wheel being adapted to retard the rotation of one spool as the apron is unwound therefrom by said drive roller and to rotate the other for winding the apron thereon as it passes from said roller.
45. 7. In an indicator, an apron having spools for receiving the same, a drive roller for moving said apron, a ratchet wheel in operative connection with said roller, a dog adapted to engage said ratchet wheel, a support for the dog, and electrically actuated means in yielding connection with said support for operating the same to rotate said ratchet wheel and a catch adapted to hold said electrically actuated means at one limit of its stroke and to insure complete movement of the drive roller and apron.
50. 8. In an indicator, an apron, spools for receiving the apron, a drive roller for moving said apron, driving means for rotating said roller in both directions, a friction wheel, connecting mechanism between said driving means and friction wheel for rotating the latter in one direction only, and friction wheels on the spools in yielding engagement with said first mentioned friction wheel for rotating said spools to thereby retard the unwinding of the apron from one spool while it is wound on the other spool.
55. 9. In an indicator, an apron, spools for receiving the apron, a drive roller for moving said apron, a drive shaft in gear with said roller, means for driving said shaft, a driven shaft in operative connection with and adapted to rotate said spools, a ratchet disk on said driven shaft, a pair of idler sprockets on said shaft driven respectively by said roller and drive shaft, and arms on said sprockets in engagement with said disk for rotating the same in one direction.
60. 10. In an indicator, an apron, spools for said apron, a drive roller for moving the apron, a ratchet wheel in operative connection with said roller, a support, a dog on said support, means for engaging said dog with said ratchet to rotate the same in either direction, a spring to hold said support in normal position, a magnet for operating said support to rotate said ratchet, a friction wheel in operative connection with said drive roller adapted to retard the rotation of one of said spools as the apron is unwound therefrom and to rotate the other spool to wind said apron as it passes from the drive roller.

11. In an indicator, an apron, having spools for receiving the same, a drive roller for moving said apron, a ratchet wheel in operative connection with said roller, an electrically actuated support, a dog on said support, dog magnets on the support for engaging said dog with said ratchet to rotate the same in either direction, a source of electric current, an electrically actuated reversing switch for connecting said dog magnets and source of current, a switch, and drops for operating said switch to connect said electrically actuated support and said reverse switch with the source of current.
12. In an indicator, an apron having spools for receiving the same, a drive roller for moving the apron, electrically actuated driving means for rotating said roller, dog magnets for reversing the operation of said driving means, a source of electric current, a reversing switch comprising a plurality of diametrically opposed contact plates, the opposite plates being alternately connected with said dog magnets, a ratchet wheel, a spring arm on said wheel adapted to engage opposite contact plates, a pawl in engagement with said ratchet wheel, a reversing switch magnet adapted to operate said pawl, a switch, and drops for operating
13. In an indicator, for electric cars, the combination with the car reverse lever of an apron having spools for receiving the same, a drive roller for moving the apron, a ratchet wheel in operative connection with said roller, an electrically actuated support, a dog on said support, dog magnets on the support for engaging said dog with said ratchet to rotate the same in either direction, a source of electric current, an electrically actuated reversing switch in circuit with said reverse lever for connecting said dog magnets and source of current, a switch and drops for operating said switch to connect said electrically actuated support and reversing switch with the source of current.

In testimony whereof, we have signed our names to this specification in the presence of two subscribing witnesses.
